BOTTLE CAP

Arthur R. Pollock, Piqua, Ohio, assignor to The
Toledo Bottle Cap Co., Toledo, Ohio, a corpora-
tion of Ohio

Application June 18, 1932, Serial No. 617,975

2 Claims. (Cl. 215—38)

This invention relates to caps of the hood-type particularly adapted for use on milk bottles in addition to the stopper members customarily employed for closing the mouths of such bottles.

5 The primary object of the invention is the provision of a cap of this character comprising a single piece of pliant material such as a heavy or stiff grade of paper, folded in such manner as to form a cap to fit down over the mouth end of a bottle and to provide integral self-contained locking means for firmly retaining the lower edge of the skirt portion in holding engagement with the contracted portion of the bottle neck immediately below the shouldered mouth lip.

10 15 The invention is fully described in the following specification, and several embodiments thereof illustrated in the accompanying drawings, in which—

20 Figure 1 is a side elevation of a cap embodying one form of the invention applied to a milk bottle, with a portion of the cap broken away. Fig. 2 is a section on the line 2—2 in Fig. 1. Fig. 3 is a reduced plan of the blank from which the cap is formed. Fig. 4 is a central vertical section 25 of a cap formed from said blank with the locking tongue members thereof in unlocked position. Fig. 5 is a side elevation of a slightly different form of cap, with the locking tongues in unlocked position. Fig. 6 is a side elevation of such cap 30 as it appears applied to the mouth of a bottle with the tongues in locked position. Fig. 7 is a section on the line 7—7 in Fig. 5. Fig. 8 is a plan of a blank from which the cap shown in Figs. 5, 6 and 7 is formed, and Fig. 9 is a blank modified 35 slightly from that of Fig. 3.

40 A cap of the form shown in Figs. 1, 2 and 4 is made from a substantially square blank of pliant material, such for instance as a heavy or rather stiff grade of paper, scored to provide folding lines and dividing the blank into a central polygonal top portion 1 and a surrounding marginal skirt portion 2, as shown in Fig. 3. The skirt is also divided by the scoring into a plurality of main body panels 3 and tongue portions 4 alternately arranged and separated from each other by triangle fold or crimp sections 5.

45 The top panel portion 1 should comprise a regular polygon with an even number of sides greater than four, which number in this form of the invention is eight, and if the blank is of square form, as shown, the sides of the top panel should be so disposed that four of them are parallel to the blank sides, and four face the respective corners of the blank. The skirt sections 3 project from the sides which are parallel

to the blank sides and the skirt sections 4 project from the sides which face the blank corners, and the inner ends of each of such sections are co-extensive with the length of the sides from which they project. The body sections 3 of the skirt gradually broaden from their inner ends outwardly, and the tongue sections 4 gradually narrow from their inner ends outwardly along the respective lines defining the interposed triangular crimp sections 5. The lines of each section 5 diverge outwardly from a point of connection of the adjacent sides of the top panel 1, and the tongue sections 4 are disposed at the corners of the blank, as shown, so that such sections are longer than the sections 3.

50 When the skirt portion 2 is folded down with respect to the top portion 1, the crimp sections 5 and attached side edge portions of the body sections 3 fold inwardly under or at the inner side of the respective side edges of the tongue sections 4, such folding, due to the triangular shape of the crimp sections 5, causing a drawing-in or contraction of the lower edge portion of the skirt about the bottle neck relative to the upper or inner edge thereof, as shown in Fig. 1. The free ends of the tongue sections now project below the skirt edge, as shown in Fig. 4, and are then tucked within the cap between the skirt edge and bottle neck to the full permissible extent, so that the tongues wrap closely around the respective 55 end edge portions of the body sections 3 which they lap, and hold the lower edge of the skirt against expansion, thus resisting its withdrawal from engagement with the bottle. It is apparent that any spreading, pull or expanding force applied to the skirt portion of the cap to release it from a bottle neck will cause the lower end edge portions of the skirt sections 3 to bear outwardly with the fold of the tongues so that the tongues resist a loosening of the engagement of the cap 60 with the bottle.

55 In the form of the invention shown in Figs. 5, 6 and 7, the construction is substantially the same as in Figs. 1 and 4, except that in folding the skirt, the side edge portions of the body sections and the triangular crimp sections thereof are folded over or lap the outer sides instead of the inner sides of the body portions of the locking tongues, so that the free portions of the tongues projecting below the skirt may be turned 65 outwardly and upwardly around the coacting end edge portions of the body sections and then have their ends inserted through holding slits provided in the inner end portions of the respective tongues.

110

One form of blank for forming the cap, shown in Figs. 5, 6 and 7, is shown in Fig. 8, and is substantially the same as the blank shown in Fig. 3, with the exception that the tongues are of somewhat greater length, the extensions thereof being formed by corner extensions of the blank, and the sides of the blank intermediate the tongues being notched to cut away surplus material instead of being left straight as shown in Fig. 3.

- 10 In this form of the invention, 11 designates the central top portion of the blank, 12 the skirt portion thereof, and 13, 14 and 15 the body, tongue and triangular crimp sections, respectively, of the skirt portion. The free ends of the 15 tongues, when interlocked with the cap, extend through slits 16 provided in the inner end portions of the respective tongues between the connected lapping portions of the skirt. It will be noted that the outer end portions of the crimp 20 sections 15, which extend beyond the lower edges of the sections 13, when folded, are cut away, thus making the portions of the tongues 14, which project beyond the skirt, of single thickness, as shown in Fig. 5.
- 25 Fig. 9 is a blank for forming a cap similar to the cap of Figs. 1, 2 and 4, except that the center or top panel portion, designated 21, comprises a six-sided instead of an eight-sided polygon. Accordingly, the blank resembles more the shape 30 of the equilateral triangle than it does a square. In this form, 22 designates the skirt portion, and 23, 24 and 25 the body, tongue and triangular crimp sections, respectively, of the skirt portion.
- 35 It is apparent that I have provided a hood-type of cap for milk bottles, or the like, which is composed of a single piece of pliant material scored or weakened along predetermined lines to facilitate a folding of the skirt portion of the cap

down around the neck of a milk bottle and such skirt portion has integral means for locking it in folded sealing relation to the bottle neck, thus eliminating the use of bands and other separate-piece means commonly employed for retaining a hood cap in engagement with a bottle neck.

I wish it understood that my invention is not limited to any specific form, construction or arrangement of the parts, as it is capable of numerous modifications and changes without departing from the spirit of the claims.

Having thus described my invention, what I claim as new, and desire to secure by United States Letters Patent, is:

1. A bottle cap of foldable material having a top portion of polygonal form with a number of sides greater than four, a skirt integrally attached to and depending from the edge of the top portion and having a plurality of body sections and a plurality of locking sections adapted to lap adjacent portions of the body sections and engage around the free end edges thereof to retain the skirt in contracted bottle neck engaging position, said body and locking sections projecting alternately from successive sides of the top portion, said skirt having slits with which the free ends of the tongues are interengaged to retain the sections in cap form.
2. A bottle cap of pliant material having a top portion and a marginal depending skirt portion, the skirt portion having pairs of opposed crimps at spaced intervals therearound and also having a locking tongue intermediate each pair of crimps projecting below and adapted to engage around the free end edges of such crimps and resist an expansion of the skirt, said skirt having slits with which the locking tongues interengage to retain them in locking position.

ARTHUR R. POLLOCK.
